(57) **CLAIM**

The ornamental design for a two-sided storage bin, as shown and described.

DESCRIPTION

FIG. 1 is a perspective view of the two-sided storage bin; FIG. 2 is a front elevational view of the two-sided storage bin;

FIG. 3 is a rear elevational view of the two-sided storage bin; FIG. 4 is a left side elevational view of the two-sided storage bin, the opposite side of which is identical;

FIG. 5 is a top plan view of the two-sided storage bin; and, FIG. 6 is a bottom plan view of the two-sided storage bin. The broken lines shown in the drawings are for illustrative purposes only and form no part of the claimed design.
